Application November 16, 1951, Serial No. 17,453

Term of patent 14 years

(Cl. D85—2)

To all whom it may concern:

Be it known that we, George L. Phillips and Louis E. Terry, both citizens of the United States, residing at Newkirk, in the county of Kay, and State of Oklahoma and Ponca City, in the county of Kay, and State of Oklahoma, respectively, have invented a new, original, and ornamental Design for a Cigarette Service Tray, of which the following is a specification, reference being had to the accompanying drawing, forming part thereof.

Fig. 1 is a top plan view of a cigarette service tray, showing our new design.

Fig. 2 is an edge view of Fig. 1.

Fig. 3 is an edge view of Fig. 1, looking in the direction of arrow 3 in said Fig. 1.

Fig. 4 is a cross sectional view of a cigarette service tray, taken on line 4—4 in Fig. 1.

We claim:

The ornamental design for a cigarette service tray, substantially as shown.

GEORGE L. PHILLIPS.
LOUIS E. TERRY.
